HOSE SUPPORTER

Filed Sept. 22, 1930

INVENTOR.

Isidor Roth
BY
Brayton Richards

ATTORNEY.

UNITED STATES PATENT OFFICE

ISIDOR ROTH, OF CHICAGO, ILLINOIS, ASSIGNOR TO NATURES RIVAL CO., OF CHICAGO,
ILLINOIS, A CORPORATION OF ILLINOIS

HOSE SUPPORTER

Application filed September 22, 1930. Serial No. 483,425.

The invention relates to improvements in hose supporters especially adapted for use in conjunction with corsets, brassières, combination garments and the like, to depend therefrom for attaching hose thereto, the primary object of the invention being the provision of an improved construction and arrangement of this character which is of simple construction, capable of economical manufacture and highly efficient in use.

Another object of the invention is the provision of an improved construction of this character which is so constructed as to be adjustable and to completely cover and protect the adjustable fastenings.

Another object of the invention is the provision of an improved construction of this character which is adjustable in length, without the use of exposed metal parts for effecting such adjustment.

Other objects will appear hereinafter.

The invention consists in the combinations and arrangements of parts hereinafter described and claimed.

The invention will be best understood by reference to the accompanying drawing forming a part of this specification, and in which

Fig. 1 is an outer face view of a hose supporter embodying the invention;

Fig. 2 an interior view of the same;

Fig. 3 a partial section taken substantially on line 3—3 of Fig. 2; and

Fig. 4 an interior view of the webs employed in the supporter shown with the hose fastener removed.

The embodiment of the invention illustrated in the drawing comprises an outer depending main supporting elastic web 5, having an inner narrower supplemental attaching web 6 arranged against the inner side thereof. The supplemental web 6 is in the form of a strip of button hole tape having button holes 7 therein, is co-extensive in length with the main web 5, and is secured thereto at both top and bottom, being otherwise free therefrom. Both of the webs are permanently secured at their upper ends to the lower edge of the supporting garment 8, which may be in the form of a corset, brassière, combination garment or the like.

The attachment of the webs 5 and 6 to the garment 8 is preferably accomplished by incorporating the upper ends of said webs directly into the lower portion of the garment, as best shown in Fig. 3. At its lower end the main web 5 is folded and secured as shown over the lower end of the supplemental web 6 to form a triangular point 9, and a button 10 is secured to the inner side of this triangular point 9, as shown, and in position to engage with anyone of the button holes 7 when the lower ends of the webs are folded upwardly, as indicated in Figs. 2 and 3.

Associated with the said webs 5 and 6 is a hose fastener 11 of any usual or desired construction, the one illustrated being provided with a wire loop 12 at its upper end through which the lower ends of the webs 5 and 6 slide freely. In use the hose fastener 11 is slidably engaged with the lower end of the webs 5 and 6, said lower ends being folded upwardly and inwardly to form a supporting loop for the purpose, and the button 10 is engaged with the proper button hole 7 to adjust the effective length of the supporter as desired, the hose fastener 11 being employed in the usual manner for supporting the hose of the wearer.

By this arrangement a hose supporter is provided which is of simple construction, capable of economical manufacture, and highly efficient in use. The means of adjustment are completely covered and protected so as to be invisible from the outer side of the wearer's garments. There are no projecting free ends of tape or the like and no metal parts, exposed or otherwise, in the adjusting means. The hose fastener may be readily removed and replaced when desired. The specific form and arrangement of parts constitutes a simple and effective one for the purpose.

While I have illustrated and described the preferred form of construction for carrying my invention into effect, this is capable of variation and modification without departing from the spirit of the invention. I therefore do not wish to be limited to the precise details set forth, but desire to avail myself

of such variations and modifications as fall within the scope of the appended claims.

Having thus fully described my invention, what I claim as new and desire to secure by Letters Patent is:

1. A hose supporter comprising a main depending supporting web; a supplemental attaching web in the form of a tape having button holes arranged against the inner side of said main web and secured thereto at top and bottom, being otherwise free therefrom; a hose fastener having a loop at its upper end slidably engaging the lower end of both said main and supplemental webs; and a button on the inner side of said main web at the extreme lower end thereof adapted and arranged to engage the different button holes in said supplemental web.

2. A hose supporter comprising a main depending supporting web; a supplemental attaching web in the form of a tape having button holes resting against the inner side of said main web and coextensive in length therewith and secured thereto at top and bottom, being otherwise free therefrom; a hose fastener provided with a loop at its upper end sliding freely on said webs; and a button at the extreme lower end of said main web adapted and arranged to engage the button holes in said supplemental web.

3. The combination with a supporting garment of a main hose supporting web secured thereto and depending therefrom; a supplemental attaching web in the form of a tape having button holes resting against the inner side of said main web, co-extensive in length therewith and secured thereto at top and bottom, being otherwise free therefrom, the upper ends of both of said webs being incorporated in and secured to the lower portion of said supporting garment, the lower end of said main web being folded inwardly into the form of a triangular point and secured over and to the lower end of said supplemental web; a hose fastener provided with a loop at its upper end sliding freely on said webs; and a button secured to the inner side of said triangular point on said main web adapted and arranged to engage the button holes in said supplemental web.

4. A hose supporter comprising a main depending supporting web; a supplemental attaching web in the form of a tape narrower than said main web, co-extensive in length therewith and having spaced button holes therein, said supplemental web being arranged centrally against the inner side of said main web and secured thereto at top and bottom, being otherwise free therefrom; a hose fastener having sliding engagement with the lower ends of both said main and supplemental webs; and a button on the inner side of said main web at the extreme lower end thereof adapted and arranged to engage the

different button holes in said supplemental web.

In witness whereof, I have hereunto set my hand this 18th day of September, 1930.
